CLAIM

The ornamental design for a service tray, as shown and described.

DESCRIPTION

FIG. 1 is a perspective view of a service tray, showing my new design;

FIG. 2 is a front elevation view thereof;

FIG. 3 is a rear elevation view thereof;

FIG. 4 is a left-side elevation view thereof;

FIG. 5 is a right-side elevation view thereof; and,

FIG. 6 is a top plan view thereof.

The broken lines shown in the drawings depict portions of the service tray that form no part of the claimed design.
